UNITED STATES PATENT OFFICE.

FREDERICK F. HORN, OF COLORADO SPRINGS, COLORADO.

DESIGN FOR A SPOON.

SPECIFICATION forming part of Design No. 22,629, dated July 18, 1893.

Application filed May 29, 1893. Serial No. 475,971. Term of patent 3½ years.

To all whom it may concern:

Be it known that I, FREDERICK F. HORN, a citizen of the United States, residing at Colorado Springs, in the county of El Paso and State of Colorado, have invented and produced a new and original Design for Spoons, of which the following is a specification, reference being had to the accompanying drawing, which represents a plan view of a spoon having my new and original design thereon.

In the drawing, A designates the bowl. B is the shank, C the stem, and D the handle. The shank has the prongs c, c, which extend laterally beyond the bowl, and extending from the prongs, in line with the shank, is the spur or tooth E which extends into the bowl A.

The leading feature of my design is the representation of a man sitting on a hillside holding a gun in his hands. Below the above described representation, which is engraved or etched into the bowl of the spoon, is space for any suitable words or inscription.

What I claim, and desire to protect by Letters Patent, is—

The design for a spoon substantially as herein described.

In testimony whereof I hereunto set my hand in the presence of two witnesses,

FREDERICK F. HORN.

Witnesses:

BURL B. WALKER,
W. E. GOWANE.
